UNITED STATES PATENT OFFICE

JESSE G. KING, OF DAYTON, OHIO, ASSIGNOR TO FRIGIDAIRE CORPORATION, OF DAYTON, OHIO, A CORPORATION OF DELAWARE

REFRIGERATING APPARATUS

Application filed October 31, 1928. Serial No. 316,273.

This invention relates to refrigerating apparatus and more particularly to an insulated and refrigerated tank provided with means for cooling its contents.

5 An object of this invention is to provide an insulated tank having refrigerant evaporating means placed within the tank which means may be removed through the cover of the tank.

10 Another object of this invention is to provide a tank with refrigerant evaporating means, the refrigerant evaporating means being so supported that it may be removed without the necessity of emptying the entire 15 contents of the tank.

Further objects and advantages of the present invention will be apparent from the following description, reference being had to the accompanying drawings, wherein a 20 preferred form of the present invention is clearly shown.

In the drawings:

Fig. 1 is a top plan view of a tank embodying features of this invention;

25 Fig. 2 is an enlarged cross sectional view taken along the line 2—2 of Fig. 1;

Fig. 3 is a side view with parts in cross section of a slightly modified form of this invention;

30 Fig. 4 is a top plan view of refrigerant evaporating means embodying features of this invention;

Fig. 5 is a vertical cross section of Fig. 4;

35 Fig. 6 is another vertical cross section taken transversely to Fig. 5 with the float control omitted; and

Fig. 7 is a vertical cross sectional view of a modified form of this invention.

An apparatus embodying features of this 40 invention may include an insulated tank generally designated as 20 which may be rectangular in horizontal cross section, with insulation on the sides and bottom. This insulated tank may be provided with a refrigerant evaporator generally designated as 21. The refrigerant evaporator may be part of a mechanical and automatic refrigerating apparatus. The refrigerating apparatus may include any suitable type of refrigerant 45 liquefying means such as an electrically

driven compressor, not shown, which may deliver compressed refrigerant to a condenser, not shown, from whence the liquefied refrigerant may be delivered through the pipe 22 to the evaporating means 21. The evaporated refrigerant may be returned through the pipe 23 to the compressor. Any type of automatic control for stopping and starting the electrically driven compressor may be used. For instance, a snap switch, not shown, 55 operated by an expandible bellows, not shown, connected to the pipes 23 may be used for starting and stopping the electrically driven compressor. The parts not shown are in common use and hence it is deemed unnecessary 60 at present to illustrate the same on the drawings.

In one embodiment of this invention the tank 20 may be the tank of an ice cream cabinet. Thus, as shown in Figs. 1 and 2, an ice 70 cream cabinet may be provided with a metal insulated tank 30 supported by a top frame member 31, which may be made of wood if desired. The top frame member 31 may be supported by a box-like metal framework 32, which may include vertical and horizontal corner angle irons suitably joined at their ends as by welding or riveting. The tank 30 may be provided with a metallic cover 33 and within the tank may be placed a body of ordinary noncongealable liquid 34, such as a solution of calcium chloride or a solution of alcohol. The cover 33, in the embodiment shown in Figs. 1 and 2, may include a downwardly directed rectangular or box-like recess 35, 75 which recess may be provided with a horizontal bottom 36. The bottom 36, as part of the cover 33, may be provided with an opening 37, through which opening the refrigerant evaporating means, which is inside of 80 the tank 30, may be removed. In the embodiment shown in Fig. 2 the refrigerant evaporating means which cools the liquid in the tank 30 may include a plurality of downwardly directed tubes 38. These tubes 38 85 may be supported from a plate 39 on top of which may be placed a boiler 40, for instance of cylindrical shape, in which is located a float mechanism 41^a adapted to control a valve member 42 which controls the 90

entrance of refrigerant from the pipe 22. A refrigerant return funnel 43 may be connected to the pipe 23. Members 41^a, 42 and 43 may be mounted on a removable plate 44 in the manner shown in the patent to R. G. Osborn, No. 1,556,708, patented Oct. 13, 1925, so that the members 41^a, 42 and 43 may be removed as a unit with the plate 44 from the cylindrical boiler for repair or adjustment.

The refrigerant evaporating means, when it includes a boiler, may have the boiler inside of the tank to be refrigerated. The boiler may be placed outside of the tank, however, and when so placed, the boiler may not be part of the evaporating means and the name "boiler" is only applicable to indicate its shape. When it is desired to place the boiler 40 outside of the tank, however, the plate 39 may be soldered to the boiler 40, which may be cylindrical if desired, by any suitable means such as by a suitable solder. The boiler 40 may be provided with a long opening 45 along the bottom. The depending pipes 38 may be soldered to the plate 39 so that when the plate 39 is secured to the boiler 40 a complete passage is provided between the boiler 40 and the tubes 38. The tubes 38, as one form of the invention, may be downwardly looped with their two ends secured to the plate 39 as shown in Fig. 6. It is thus seen that the refrigerant evaporating means for the tank, which in Fig. 2 includes the pipes 38, are placed within the tank 30. The opening 37 in the metal cover 33 is closed by the plate 39 with a gasket 50 interposed there between and secured by means of the bolts 41 if desired. The refrigerant evaporating means 38 may be removed through the opening 37 after the opening 37 has been uncovered by the removal of the plate 39. It is to be seen that the tank 30 need not be emptied below the level of the opening 37 in order to provide for the removal of the evaporating means 21.

In an ice cream cabinet of the type disclosed, the tank 30 may have placed therein a plurality of food compartments 51, which may be cylindrical sleeves with their open ends connected to the cover 33 for the reception of ice cream cans or the like. An insulated cover 53 may be placed over the metal cover 33 in order to prevent refrigeration losses through the cover 33. Cylindrical insulated lids 52 may be provided to be in alignment with the sleeves 51 and may rest on the insulated cover 53.

Means forming insulation at the opening 57 permitting the removal of the evaporating means may be provided. Thus a rectangularly insulated lid 54 may be placed over the recess 35 and insulating material such as Kapock 56 may be placed within the recess after the evaporator 21 has been secured in place. An opening 57, suitably lined by a sleeve, if desired, may be made in the insu-

lated cover 53 and may be in axial alignment with the opening 37 in order to provide for the vertical removal or insertion of the evaporator 21.

The ice cream cabinet may be provided with side panels 58 secured to the metal frames 32, if desired. One of these panels 58 may be provided with an opening closed by a plate 59. Upon the removal of the plate 59, as by loosening the screws 60, some of the insulating material 56 may be removed laterally and the plate 44 (Fig. 5) may be removed laterally from the cabinet through the last named opening for the repair or adjustment of the parts carried by said plate 44.

In the modification shown in Fig. 7 the evaporating means to be placed inside of the tank may include the boiler 40^a and the depending pipes or loops 38. The opening 37^a may be provided in the top 33^a of a tank 30^a similar to the tank shown in Fig. 2 with the exception that the downwardly directed recess 35 may be omitted. The boiler 40^a may be provided with a flange 61, which is adapted to be secured to the side 62 of the tank 30^a, for instance, by providing a ring 63 pinching the side 62 of the tank between the ring 63 and the flange 61 by means of the bolts 64. A plate, not shown, and similar to the plate 44 of Fig. 5 may be secured to the boiler 40^a inside of the flange construction 61 so that such a plate may be removed laterally by the removal of a plate 59^a similarly as in the case of Fig. 2. The construction of the plate 44 is more fully disclosed in the patent to Osborn herein referred to. When it is desired to remove the entire refrigerant evaporating means including the boiler 40^a and loops or tubes 38, the plate 39^a may be removed, for instance, by loosening the bolts 65. The bolts 64 may be loosened and the pipes 22 and 23 may be disconnected after which the evaporating means may be removed through the opening 37^a. It is thus seen that, in this embodiment, the evaporating means may be removed through the opening 37^a in the metal cover 33^a, and that the liquid in the tank need not be emptied below the opening in the side 62 of the tank.

In the embodiment shown in Fig. 3, a drinking water cooling apparatus or cabinet 70 may be provided with an insulated tank 71. This tank may be rectangular in horizontal cross section also if desired. Drinking water may be introduced into the tank 71 through the inlet pipe 72 and may be withdrawn through the faucet 73. A waste water drain means 74 may be mounted on the water cooling apparatus and the pipe 75 may lead to any waste water receptacle desired. A box-like metal frame 76 may support the tank 71, for instance, through the medium of a stiff piece of insulation 77^a on

the bottom of the tank and within this framework insulation 77 may be placed around the sides and bottom of the tank in a manner somewhat similar to the embodiment shown in Fig. 2. The tank 71 may be provided with a metal cover 78 which, in this particular embodiment, may be formed integral with the sides of the tank. An opening 79b may be placed in the cover 78 and through this opening the pipes 38 may be removed from the tank. A plate 39 may be provided by closing the opening 79b in a manner similar to the embodiment shown in Fig. 2. An insulated cover 79 may be provided for the cover 78. The cover 79 may include insulation 80 placed around the boiler 40 in order to provide an insulated cover with the aid of the plate 79a. The evaporating means may be removed after the removal of cover 79 by loosening the bolts 41 in a manner similar to Fig. 2. Metal panels 81 may be placed around the sides of the cabinet 70 and an opening in the side of the cabinet may be covered by the removable plate 82 similar to the plate 59 so that the evaporator plate 44 may be removed laterally in the same manner as shown in Fig. 2. In this particular embodiment the evaporating means 38 may be removed from the tank without disturbing the contents of the tank since after the water under pressure has been turned off no water will flow out of the tank upon the removal of the plate 39 from the cover 78.

The refrigerant liquefying unit, such as an electrically driven compressor, together with an air cooled condenser and liquid refrigerant receiver may be placed in the lower compartment 85 of the cabinet 70. This refrigerant liquefying unit may be connected to the evaporator by means of the pipes 22 and 23.

While the form of embodiment of the invention as herein disclosed, constitutes a preferred form, it is to be understood that other forms might be adopted, all coming within the scope of the claims which follow.

What is claimed is as follows:

1. A refrigerating apparatus comprising a closed tank for liquid to be cooled, said tank having an opening, a plate for closing said opening, refrigerant evaporating means removable from said tank through said opening, said evaporating means comprising a refrigerant header on one side of said plate and ducts on the other side of said plate extending into said tank and connected to said header.

2. A refrigerating apparatus comprising a closed tank for liquid to be cooled, said tank having an opening, a plate for closing said opening, refrigerant evaporating means removable from said tank through said opening, said opening being located in the top of said tank, said plate when in position on said

tank being horizontal, with said header above and said ducts below said plate.

3. A refrigerating apparatus comprising a tank for liquid to be cooled, a cover for said tank having an opening, a plate on said cover for closing said opening, refrigerant evaporating means removable from said tank comprising a header secured above said plate, and refrigerant ducts connected to said header and extending from the bottom of said plate into said tank, said plate, header and ducts being removable from said tank.

In testimony whereof I hereto affix my signature.
